UNITED STATES PATENT OFFICE.

MARSHALL P. MAXWELL, OF BROOKLYN, AND JOEL S. LAWSON, OF ST. JAMES, NEW YORK.

ELECTRIC SWITCH.

1,350,107.

Specification of Letters Patent. Patented Aug. 17, 1920.

Application filed January 4, 1918. Serial No. 210,383.

To all whom it may concern:

Be it known that we, MARSHALL P. MAXWELL and JOEL S. LAWSON, both citizens of the United States of America, residing in the borough of Brooklyn, county of Kings, and State of New York, and at St. James, Long Island, in the county of Suffolk and State of New York, respectively, have invented certain new and useful Improvements in Electric Switches, of which the following is a specification.

Our invention relates to electric switches and particularly to switches for use in power lines of heavy capacity, the object of our invention being to provide an air gap switch capable of breaking a current of very high voltage, and having a simple and efficient operating mechanism and a general construction adapted to fulfil with efficiency the heavy demands placed upon the switch, while at the same time, maintaining the structure fundamentally simple and free from easily disarranged complications and also relatively inexpensive to manufacture.

In the accompanying drawings,

Figure 1 is a plan of a switch installation in which our invention is embodied in one form;

Fig. 2 is a side elevation thereof;

Fig. 3 is a vertical section through one of the switch contacts;

Fig. 4 is a section on the line 4—4, Fig. 2; and

Fig. 5 is an inverted plan of the mechanism shown in Fig. 4.

In all switches for power lines in which the voltage is very high, it is customary to provide a three unit switch gang for the three phases of the circuit, and the present switch is of such type, the construction for each phase being identical. A single switch unit, therefore, suffices to disclose the invention, and we have, for this reason, omitted in Figs. 1 and 2 the two switches which co-operate with the one illustrated.

Each switch is mounted upon a base bar 10 and is insulated therefrom in any suitable manner, as by the three post insulators 11, 12, and 13. The line wire 14 for the unit here shown is secured at 15 to one of the switch terminals, being gripped at 16 by a cable clamp engaging the strain insulator 17, attached to the base bar 10 by a

hook 18. The other end of the cable 14 is secured at 19 to the other terminal of the 55 switch and passes therefrom to the links 20 and 21, the latter being jointed to a cable clamp 22, which engages the strain insulator 23 secured to the base 10 by a hook 24.

The post insulator 13 is stationary and 60 carries on its cap plate 25 the housing 26 for the stationary switch terminal 27. The post insulator 12 is also stationary and carries on its cap plate 28 a supporting guide 29 upon which reciprocates the switch bar 65 30 carrying, at one end, the movable switch terminal 31. The post insulator 11 rotates in a suitable bearing 32 on the base 10 and is engaged by a rotary stem 33 which may be operated in any suitable way—usually by 70 a hand lever (not shown) at its lower end. To the cap plate 34 of the insulator is rigidly attached the toggle lever arm 35, jointed at 36 to its co-operating arm 37, which in turn is jointed at 38 to the sliding switch 75 bar 30.

Upon rotation of the insulator 11, the toggle lever 35—37 forces the switch bar 30 in a straight line to the left and thus brings the terminal 31, carried thereby, into engagement with the stationary terminal 27, thereby establishing the circuit through the switch. As the switch bar 30 moves forward, the link 20, jointed at 39 thereto, is drawn forward thereby and continues to 85 support the slack of the cable well out of the way of the metallic parts on the base 10.

Associated with the switch terminals 27 and 31 are arcing horns 40 and 41. The horn 41 is secured in permanent position 90 with relation to the contact 31, and is so positioned slightly in advance of the contact 31 as to protect the latter from danger should an arc form at the air gap on the opening of the switch. The horn 40 is slidably mounted upon the casing 26 of the stationary contact 27. To this end it is provided, at its lower end, with a supporting foot 42, sliding in a channel 43 in the casing 26 and provided with a stem 44, which 100 passes through a guiding abutment plate 45, between which and the foot piece 42 is arranged a spring 46, coiled around the stem 44. At the outer end of the stem 44 is provided a stop nut 47 which determines the extent of the outward movement of the horn 105

under the action of the spring 46. A cap 48 may be provided to house the end of the rod 44. A hood 49 may be carried by the horn 40 to protect the parts against sleet, snow, 5 and rain.

In normal position, the horn 40 projects beyond the end of the switch terminal 27, so that the arc is broken between the base of the horns 40 and 41, rather than between the 10 contacts 27 and 31, on the opening of the switch. When the switch is closed, the base of the horn 41 engages the base of the horn 40 and forces the latter to the left into the position shown in dotted lines in Fig. 2 and 15 in full lines in Fig. 3, thus permitting the jack terminal 31 to seat itself deeply between the legs of the coöperating terminal 27.

In order to insure the break at the arcing horns, a latch 50 is pivoted at 51 to the foot 20 of the horn 40. The nose 52 of the latch is lifted through its bearing on the cross pin 53 as the horn moves to the left, and is drawn up into engagement with the notch 25 520 in the lower face of the contact 31, thus mechanically securing the contact and horn together. When the switch is opened, the horn 40 is pulled out by this positive engagement of the latch 50 on its foot piece 30 with the contact 31, as well as by the effort 35 of the spring 46. At the moment the jack terminal 31 leaves the terminal 27, the nose 52 of the latch is forced down out of engagement with the terminal 31 by the lug 35 54 at the opposite end thereof, which, at this moment, engages the pin 53. The final breaking of the connection between the arcing horns and not between the contacts 27 and 31, is thus assured.

40 As previously stated, high power switches of this type are universally arranged in a three unit gang, one unit for each of the three phases of the line. It is highly desirable that the breaks be simultaneous at 45 each switch. To insure such simultaneous operation of the three switches, we provide a lever interconnection, such as that shown in Figs. 4 and 5, for operating the rotary insulators 11, 111, and 211 of the several 50 switch units supported upon the base bars 10, 110, and 210. As here shown, the stem 33 carries a star plate 55 with four arms 56, 57, 58, and 59. The stem 60 of the insulator 111 has fast therewith a spider, the arms 61 55 and 62 of which are connected by links 63 and 64 with the star arms 56 and 57. Similarly, the stem 65 of the insulator 211 has a spider, the arms 66 and 67 of which are connected by links 68 and 69 with the star 60 arms 58 and 59. The relation of the various arms and links is such that the parallel-ruler motion of the link pairs 63-64, 68-69 insures the synchronous rotation of the insulators 11, 111, and 211. While general 65 synchronism is attained through the linkage

arrangement just described, the delicate final adjustment is made through the precise location of the stop nuts on the stems 44. The adjustment at this point permits the precise timing of the parting of the several pairs 70 of horns in the switch group.

The construction as a whole is both simple and rugged. The reciprocation of the contact 31 affords the greatest possible break for a given arc of rotation of the insulator 75 11. The rapid separation of the contacts tends to pull out the arc and thus increases the likelihood of breaking the latter. The operating lever connection is simple and efficient. The parts of the switch are readily 80 made and are many of them of standard material. Accidental separation of the contacts is prevented by the latch 50, while the freeing of the latter after the initiation of the opening movement of the switch, is positively insured, as is also the consequent break of the current between the arcing horns. These advantages will commend themselves to those skilled in the art, but we do not limit ourselves to the precise 85 90 structure shown, which may be variously modified without departing from what we claim as our invention.

We claim:

1. An air gap switch for high voltage 95 lines, comprising a reciprocating switch bar, a rotary member and a toggle lever connection between the latter and the switch bar for operating the latter, together with means associated with said switch bar for supporting a slack portion of the wire cable out of proximity to the switch base in all positions of the switch bar.

2. An air gap switch for high voltage 105 lines, comprising a reciprocating switch bar, a rotary member and a toggle lever connection between the latter and the switch bar for operating the latter, together with pivoted links associated with said switch bar for supporting a slack portion of the wire 110 cable out of proximity to the switch base in all positions of the switch bar.

3. In an air gap switch, a fixed terminal, a slidable arcing horn associated therewith and yielding means for maintaining said 115 horns normally in advance of the terminal in the "off" position of the switch, but yieldably to permit said horn to move to a position to the rear of the engaging portion of the terminal when the switch is in "on" 120 position.

4. In an air gap switch, a fixed terminal and an associated slidable arcing horn reciprocating from a position in advance of, to a position to the rear of, the engaging portion 125 of the terminal.

5. In an air gap switch, a fixed terminal and an associated spring pressed slidable arcing horn having a normal position in advance of the terminal in the "off" position 130

of the switch, but movable to a position to the rear of the engaging portion of the terminal when the switch is in "on" position.

6. In an air gap switch, a fixed terminal, 5 a coöperating movable terminal, a movable arcing horn associated with the fixed terminal, and means extending between said movable terminal and the arcing horn for mechanically connecting the same in the closed 10 position of the switch.

7. In an air gap switch, a fixed terminal, a coöperating movable terminal, a movable arcing horn associated with the fixed terminal, and means extending between said movable terminal and the arcing horn for mechanically connecting the same in the closed 15 position of the switch, together with means for automatically establishing said connection as the switch closes.

20 8. In an air gap switch, a fixed terminal, a coöperating movable terminal, a movable arcing horn associated with the fixed terminal, and means extending between said movable terminal and the arcing horn for me-

chanically connecting the same in the closed 25 position of the switch, together with means for automatically freeing said connection as the switch opens.

9. In an air gap switch, a fixed terminal having a movable arcing horn, a coöperating 30 movable terminal and a latching device associated with said horn for locking the latter to the movable terminal in the closed position of the switch.

10. In an air gap switch, a fixed terminal 35 having a movable arcing horn, a coöperating movable terminal and a latching device associated with said horn for locking the same to the movable terminal in the closed position of the switch, but disengaging the movable terminal only toward the end of the separating movement of the same, to insure the protecting position of the horn when the switch is opened.

In testimony whereof we have signed our 45 names to this specification.

MARSHALL P. MAXWELL.
JOEL S. LAWSON.
